UNITED STATES PATENT OFFICE

2,001,874

COMPRESSING UNIT

Edward Heitman, Detroit, Mich., assignor to Kelvinator Corporation, Detroit, Mich., a corporation of Michigan

Application October 12, 1931, Serial No. 568,319

1 Claim. (Cl. 230—206)

This invention relates to mechanical refrigerating apparatus and has particular relation to refrigeration units of relatively large capacity employed in cooling show cases, meat boxes and 5 for other service of a similar character.

Some of the objects of the invention are to provide a refrigeration apparatus of this type which will be relatively quiet and efficient in operation and in which oil pumping, prevalent to 10 a greater or less degree in refrigeration units of this character, heretofore employed, will be substantially decreased.

The invention generally embraces a refrigerant condensing unit in which the compressor is provided with suction and discharge valves in the 15 head of the cylinder thereof and in which the suction line communicates with both the suction valve and the crank case of the compressor through a passage formed in the compressor wall. The rotation of the crank shaft of the compressor is in a direction such that the oil adhering to the crank will be thrown elsewhere than into the passage connecting the crank case 20 with the head of the compressor.

For a better understanding of the invention reference may now be had to the accompanying drawing forming a part of this specification, in 25 which:

Figure 1 is a side elevational view of a refrigerant condensing unit embracing the invention and in which figure a portion of the refrigerant compressor is broken away to illustrate the interior construction thereof;

Figure 2 is a fragmentary cross sectional view 30 on an enlarged scale of an upper portion of the compressor illustrated by Figure 1;

Figure 3 is a fragmentary cross sectional view of the refrigerant compressor head taken substantially on line 3—3 thereof.

Figure 4 is a fragmentary view of a refrigerator 40 embracing a refrigerant evaporating unit for cooling the interior thereof.

Referring more in detail to the refrigerating mechanism illustrated by the drawing, a refrigerator 45 embracing insulated walls 11 and 12 is provided with an evaporating unit 13 in which liquid refrigerant is vaporized and in being so vaporized absorbs the heat which is conducted through the walls of the refrigerator. The 50 evaporating unit consists principally of a float chamber 14 containing a conventional low side float, not shown, from which extends a plurality of refrigerant circulating conduits 15 joined at their outer extremities and to which are attached 55 a plurality of vertically disposed heat conducting

fins 16. Liquid refrigerant is supplied to the evaporating unit 13 through a liquid line 17 and vaporized refrigerant is exhausted through a suction conduit 18. The liquid line 17 is connected to a lower portion of a liquid receiver 19 which forms an element of a refrigerant condensing unit 21. The suction line 18 communicates at its opposite end with a suction line cut off valve 22 attached to and communicating with the suction side of a refrigerant compressor 23. Bolts 24 10 projecting through a flange 25 formed on the lower extremity of the compressor 23 serve the purpose of securing the compressor rigidly to a condensing unit base 26.

The compressor is driven by a motor 27, secured to the base 26 by brackets and bolts indicated at 28, through a belt 29 which engages a drive pulley 31 of the motor and a combination driven pulley and fly wheel 32 attached to the compressor. The motor 27 also drives a fan 33 15 which is adapted to discharge a blast of air upon a vertically disposed refrigerant condenser 35 likewise supported by the base 26 and secured rigidly to the latter upon a bracket 36 extending therefrom. One end of the condenser 35 communicates, through a conduit 37, with an outlet coupling 38 from a cavity 39 formed in the interior of a head 41 of the compressor 23. An inlet coupling 42 associated with an opposite portion of the cavity 39 communicates with one end 30 of a conduit 43 which in turn is connected at its opposite end to a discharge cut off valve 44 communicating with the high side of the compressor 23. The opposite end of the condenser 35 communicates through a conduit, not shown, with 35 an upper portion of the refrigerant receiver 39.

It will be apparent from the description of this structure that compressed refrigerant vapor discharged from the compressor 23 through the conduit 43 will pass first through the cavity 39 40 in the head 41 and then through the conduit 37 to an upper portion of the condenser 35. Liquefied refrigerant formed in the condenser 35 is discharged therefrom into the receiver from whence it is in turn conducted through the liquid 45 line 17 to the evaporating unit 13.

The compressor 23 comprises a crank case 46 having bearings formed at opposite ends thereof in which a crank shaft 47 is journaled. Connecting rods 48 and 49 journaled respectively on 50 the two throws 51 and 52 of the crank shaft 47 are adapted to reciprocate pistons 53 and 54 of the two cylinders 55 and 57 of the compressor. Both of the cylinders 55 and 57 are cast as a unit with the crank case 46. The upper ex- 55

tremities of the cylinder are covered by a plate 58 through which a plurality of inlet openings 59 and an exhaust opening 61 are formed for each cylinder. The upper surface of the plate 58 is 5 in turn covered by a valve plate 62 with which discharge valves 63 and inlet valves 64 for each of the cylinders are associated. The inlet valves 64, which are arranged on the lower side of the valve plate 62 in recesses 66 formed in the upper 10 surfaces of the plates 58, comprise relatively flat reeds 67 which cover orifices 68 formed in the plate 62, and slightly curved reeds 69 positioned immediately beyond the flat reeds and abutting the latter at opposite extremities thereof. Such 15 abutting ends of the reeds 67 and 69 are provided with aligned openings through which pins 71 project; the opposite ends of the pins being disposed in openings formed in the adjacent surfaces of the plates 58 and 62.

20 During the normal operation of the compressor 23, the reeds 67 merely curve slightly away from the orifices 68 to permit the entrance of refrigerant vapor to the cylinders on the suction stroke of either of the pistons, but in the event a greater 25 flow of gas is required through the orifices 68, the curved reeds 69 will be somewhat straightened thus permitting the reed 67 to move farther away from the seating surfaces therefor. The orifices 68 each communicate with a horizontally arranged 30 passage 72 which is formed partly in the upper surface of the valve plate 62 and in the lower surface of the cylinder head 41. Adjacent the opposite extremities of this passage and directly above the cylinders 56 and 57 are formed 35 cavities 73 which are provided for the purpose of permitting the use of valves other than the type herein illustrated.

A central portion of the passage 72 communicates with the upper extremity of a vertically 40 disposed duct 74 formed through the plates 62 and 58, and an upper portion of a compressor cylinder block 76 embracing the cylinders 56 and 57. This duct, which is arranged in the 45 block 76 at one side of but midway between the cylinders 56 and 57, communicates at its lower extremity with a cored chamber 77 formed in the cylinder block immediately above the crank case 46 and communicating with the latter through an opening 78. One side of this chamber is provided with an inlet opening 79 which 50 communicates with the suction line 48 through the suction line cut off valve 22.

A reduction in pressure in the cylinders 56 and 57, caused by the reciprocation of the pistons 53 and 54 and the operation of the valves 64, initiates a flow of gas from the suction line 48, through the opening 79 into the chamber 77, through the duct 74 in the passage 72 and into the cylinders through the orifices 68 at the opposite 55 ends of the passage 72 and the openings 59 beneath the suction valves 64. The reciprocation of the pistons 53 and 54 also tends to cause variations in pressure in the crank case 46 which are compensated for by the intermittent flow of gas between the chamber 77 and the crank case 46 60 through the opening 78.

The rotation of the crank shaft 47 is such that when it emerges from the oil contained in the crank case 46 the oil adhering to the throws of

the shaft will be thrown against the side of the crank case opposite that in which the opening 78 leading to the chamber 77 is formed. In other words, the throws of the crank will move downwardly on the side of the crank case containing the opening 78 and upwardly on the opposite side thereof. 5

The head 41 contains a second horizontally disposed passage 81 which extends the length thereof and lies substantially parallel to the 10 passage 72. The refrigerant discharge valves 63 hereinbefore mentioned are located in the passage 81 adjacent the opposite ends thereof and each valve covers a port 82 communicating with the opening 61 leading from the cylinders 56 and 57. The discharge valves 63 are somewhat similar in construction to the inlet valves 64 in that each comprises a relatively straight reed 83 which is held in position by a curved plate or stop 84, the opposite ends of 20 both the reeds and stops being provided with openings through which project studs 86 secured in openings in the valve plate 62 on opposite sides of the ports 82. Coil springs 87 are positioned between the heads of the studs 86 25 and the ends of the stops 84 for the purpose of holding the latter resiliently against the ends of the reeds. An intermediate portion of the passage 81 communicates with the discharge cut off valve 44 communicating with the discharge 30 line 43 from the compressor.

When, by reason of the reciprocation of the pistons 53 and 54 and the operation of the valves of the compressor, the pressure in the cylinders 56 and 57 is increased a predetermined amount, 35 compressed gas will be forced outwardly through the valve 63 into the passage 81 where it will flow through the duct 74 into the line 48. It is to be observed that the pistons 53 and 54 are without the usual inlet valves therein and that 40 the oil saturated gas passes not through the pistons as in ordinary refrigerant compressors but enters the head of the compressor through a separate passage and then is admitted to the cylinders through inlet valves positioned thereabove. 45

While only a preferred form of the invention is illustrated and described in detail herein, it is apparent that other structures may be devised embracing the principles of the invention within the scope of the appended claim. 50

I claim:

A refrigerant compressing unit comprising a compressor having a crankcase and including a cylinder disposed above the crankcase, a valve plate arranged to close the top of the cylinder, a piston reciprocable in the cylinder, an inlet valve carried by said plate, a wall for the compressor having a passage formed therein and an inlet leading to said passage, said passage at opposite ends being in communication with the inlet valve and the crankcase, respectively, and means for supplying refrigerant vapor mixed with oil to said passage at a point below said inlet valve, said passage having a relatively large cross sectional area as compared with said inlet whereby said vapor and oil become separated by change in velocity upon entering said passage. 60

EDWARD HEITMAN.
